(Continued)*Primary Examiner* — Karen E. Eldridge Powers*Assistant Examiner* — Jasmine Mlinarcik(74) *Attorney, Agent, or Firm* — Blake, Cassels & Graydon LLP; Wilfred P. So(57) **CLAIM**

The ornamental design for a scarf, substantially as shown and described.

DESCRIPTION

FIG. 1 is a perspective view of a scarf in a configuration illustrating the design as it appears worn on the body; FIG. 2 is a perspective view of the scarf in another configuration as worn on the body;

FIG. 3 is a front elevation view of the scarf in a flat configuration;

FIG. 4 is a rear elevation view of the scarf in a flat configuration;

FIG. 5 is a left side elevation view of the scarf in a flat configuration, with the right side elevation view being a mirror image of the left side elevation view;

FIG. 6 is a top plan view of the scarf in the flat configuration; and,

FIG. 7 is a bottom plan view of the scarf in a flat configuration.

The broken lines shown represent environmental structure and form no part of the claimed design.

1 Claim, 4 Drawing Sheets---
